UNITED STATES PATENT OFFICE.

ALFRED J. MORRISON, OF DENVER, COLORADO, ASSIGNOR OF ONE-HALF TO WILLIAM E. WARNEKE, OF DENVER, COLORADO.

COATING-MACHINE.

1,331,460.

Specification of Letters Patent. Patented Feb. 17, 1920.

Application filed December 17, 1918. Serial No. 267,195.

To all whom it may concern:

Be it known that I, ALFRED J. MORRISON, a citizen of the United States, residing at Denver, in the county of Denver and State 5 of Colorado, have invented certain new and useful Improvements in Coating-Machines, of which the following is a specification.

This invention relates to improvements in machines for coating sheets of paper or 10 other material with a liquid or semi-liquid adhesive, chemical or water-proofing substance, and more particularly to machines of the type commonly used in box factories and printing establishments to provide labels, pasters or box covers with a coating of liquid gum or other adhesive.

It is the primary object of my invention to provide in a machine of the character mentioned, certain features of construction 20 which increase the capacity and efficiency of the machine and prevent the waste and loss of labor caused by curling of the sheets, imperfect coating and irregular delivery experienced in many of the machines at present in use.

In the operation of my machine, evenly 30 coated sheets are fed at regular intervals onto a belt-conveyer which carries them to a point of discharge in a perfectly flat condition, ready for immediate or later use as the case may be.

Another object of the invention is to provide means for feeding the sheets of paper onto the coating element of the machine, 35 which are regulatable so as to adapt the machine for properly coating sheets of paper and other material irrespective of their weight and finish.

Still other objects of the invention reside 40 in mounting the coöperative parts of the machine so as to facilitate cleaning and relative adjustments and in providing means which cause the coating process to be immediately resumed after stoppage and thus

45 prevent waste of material otherwise resulting from an interrupted supply of liquid onto the coating element of the mechanism.

With the above and other objects in view, 50 all of which will fully appear in the course of the following description, my improved coating machine consists of the constructions, arrangements and combinations of coöperative devices illustrated in their preferred form in the accompanying drawings

in the various views of which like parts are similarly designated, and in which—

Figure 1 represents a plan view of the machine;

Fig. 2, a side elevation of the same;

Fig. 3, an enlarged fragmentary section 60 along the line 3—3, Fig. 2;

Fig. 4, a section taken on the line 4—4, Fig. 3;

Fig. 5, a vertical section on the line 5—5, Fig. 4; 65

Fig. 6, a fragmentary enlarged side elevation of one of the side plates at the head end of the machine, between which the coating mechanism is contained;

Fig. 7, an enlarged section through the 70 feed-gate of the machine taken on the line 7—7, Fig. 5;

Fig. 8, an enlarged section along the line 8—8, Fig. 6;

Fig. 9, a sectional view of the water-bath 75 and adjacent parts for moistening the conveying belt of the machine;

Fig. 10, an enlarged section on the line 10—10, Fig. 6;

Fig. 11, a section taken on the line 11—11, 80 Fig. 2, and

Fig. 12, a fragmentary side view of the gearing on the outside of the side plate at the head end of the machine, opposite to that shown in Fig. 6. 85

Referring more specifically to the drawings, the reference character 2 designates the supporting structure of the machine upon which the parts of its operating mechanism are coöperatively assembled. 90

The coating element of the machine which is mounted at one end of the supporting structure, comprises a pan 3 which in practice contains the liquid adhesive or other substance to be applied to the sheets of material and which in its operative position is removably supported upon the upper end of a slanting rest 4. 95

The pan has for its further support a pair of laterally projecting ears 5 which 100 rest upon lugs extending outwardly from two upright side plates 6 erected upon the supporting structure, between which the coating and feeding elements of the mechanism are assembled. 105

When it is desired to refill the pan it may be lowered and replaced without danger of spilling its contents, by sliding it along the

slanting surface of the support which is adapted to hold it in its lower position as indicated in broken lines in Fig. 4, in connection with a rod 7 extending transversely 5 between the side plates 6.

A metal roller 8 dips into the fluid contents of the pan for their transference to the surface of a coating roller 9 with which it is in contact.

10 The dipping roller 8 has oppositely extending gudgeons 10 which are mounted in eccentric openings of circular bushings 12 which are rotatably fitted in bearings 13 in the side plates.

15 The bushings 12, as shown in Fig. 6, projects beyond their bearings and extend into openings in the ends of levers 14 which move along the outside of the plates and are held in their adjusted positions by clamping

20 screws 15 extending through arcuate slots 16 in the same. The coating roller 9 is mounted for rotation about a fixed axis in bearings in the side plates and it will be seen that by proper adjustment of the levers 14

25 the bushings can be moved in their respective bearings so as to vary the distance between the two rollers in accordance with the thickness of the coating of liquid it is desired to apply to the sheets under treatment.

30 A bar 17 extending lengthwise of the dipping roller in or near the horizontal plane of its axis of rotation and in parallel and spaced relation to its circumferential surface, provides means to separate all dirt and other foreign matter from the liquid on said 35 surface as it emerges from the bath in the pan 3, and thereby prevents their being transferred to the surface of the coating roller.

40 The bar 17 has wings 18 extending along the portions of the gudgeons of the roller between its opposite ends and their respective bearings, to automatically clean them from liquid and other adhering matter.

45 The coating roller lies axially outside the vertical plane of the axis of the dipping roller so that rearward of their line of tangence a pocket 19 is formed in which a 50 small quantity of liquid is collected whenever the machine is stopped after a period of operation.

55 It is the object of this pocket to effect an immediate resumption of the coating process when the mechanism is again set in motion, by providing the surface of the coating roller with liquid in the interim during which the portion of the surface of the dipping roller emerging from the bath, moves 60 to the point at which the rollers are in contact.

65 It will be seen that by these means waste of material by imperfect coating of sheets, due to intermittent operation of the machine, is effectively avoided.

The sheets of paper which are fed onto the coating roller by the feed mechanism one type of which is hereinafter described, are lifted from its surface to pass onto a conveying belt 20, by a plurality of lifters 70 21 which are rigidly mounted upon a transverse rod 21^a between the side plates and freely rest upon the roller.

The forward edges of these lifters curve from the surface of the roller around the 75 portion of the conveying belt as it passes around the rearward one of the rollers upon which it is mounted, so that the sheets of paper which were fed onto the roller and would naturally adhere to the liquid-carrying surface thereof, are automatically separated from said surface and directed onto the forwardly moving portion of the belt.

In order to eliminate any obstructive 80 edges which may prevent the uninterrupted 85 passage of sheets of paper from the surface of the coating roller onto the curved edges of the lifters, the latter rest in narrow circumferential grooves 22 of the roller and these grooves are kept clean and free from 90 the liquid applied to the surface of the roller, by slender wire wipers 23 as shown in Fig. 5, which extend into the same from a transverse bar 24 supported between the 95 side plates.

95 As will be seen by referring to Figs. 3 and 4, a portion of each wiper 23 extends into and substantially fills its associated circumferential groove 22 in the zone of contact or tangency between the rollers 8 and 9. Since 100 such entering portions of the wipers substantially fill the grooves, the glue is practically prevented from entering thereinto from the glue pocket 19 and thus a more uniform coating of the blanks or sheets is 105 obtained.

110 The lifters are rigidly held in place on the rod 21^a and can not be displaced and injured as might occur in case they could be lifted from the grooves of the roller, into which they extend. As shown in Fig. 3, the grooves are relatively narrow and the portions of the lifters entering said grooves are of substantially the full width thereof so as to practically fill the grooves.

115 Any approved feed-mechanism may be employed. That shown consists of a traveling platform 25 upon which in practice a stack of the sheets of paper to be coated is supported, an adjustable gate 26 which 120 limits the forward movement of the sheets by operation of the platform, to one at a time, a pair of friction rollers 27 and 28 which remove the sheets from the platform, a stationary table 29 along which they pass 125 toward the coating-roller, and a guide-roller 30 which moves the sheets onto the liquid-carrying surface of the same.

130 The moving platform consists of a plurality of rubber belts 31 placed adjoiningly.

around a series of parallel horizontal rollers 32 which are rotatably supported between the side plates 6.

One of the end rollers of the series carries a pinion 33 for its operative connection with a power transmission mechanism hereinafter to be described and it is operatively connected with the roller at the opposite end of the same by a sprocket chain 34. 10 Wheels 32^a beneath the other end roller of the series hold the belts against lateral displacement.

In vertical alignment with the axis of the roller at the end of the series rearmost with 15 relation to the movement of the belts, is the gate 26 which is adjustably supported on two spaced bars 35 which are horizontally secured between the side plates.

The gate consists of a metal block 36 secured at the lower end of and in transverse relation to a stem 37 which projects loosely through aligned openings in the bars 35, and a wing-nut 38 applied to the threaded upper end of the stem and resting upon the upper 25 bar holds the block against downward movement by gravitation and the pressure of a spring 39 which is wound around the portion of the stem between the lower bar and the block 36.

30 The block is recessed along its lower edge to receive the body portion of a rubber shoe 40 which extends across said edge to engage the upper surface of a sheet passing beneath the same by movement of the rubber belts 31.

A plate 41 fastened upon the block provides a support for a movable plate 42, the lower edge of which is bent around the corresponding edge of the first-mentioned 40 plate as at 43 and is rounded to provide a gradual approach to the lower surface of the rubber shoe.

It is the object of this approach to eliminate edges and surfaces which if engaged 45 by the forward edge of the moving sheet of paper might tend to curl, bend or break the same and thereby interfere with the production of coated sheets in a flat and perfect condition, which is the primary object 50 of the present invention.

The plate 42 has a vertical slot for the passage of a clamping screw 44 by which it is held on the bars 35 and by loosening this screw it may be adjusted to regulate 55 the position of its curved lower end with relation to the surface of the rubber shoe.

The lower one, 28, of the two friction rollers is provided with a pinion 45 for its connection with the transmission mechanism 60 and the upper roller 27 has gudgeons extending loosely through vertical slots in the side plates and rests loosely upon the surface of the other roller.

The guide-roller 30 which likewise is provided with a pinion 103, is positioned at the

rearward end of the stationary table 29 and in spaced relation to the surface of the coating-roller 9 and its object is to compel sheets moved toward the coating roller by the friction-rollers 27 and 28, to engage 70 the liquid-coated circumferential surface of the same.

The gearing of the transmission mechanism by which the feed-roller 28, the guide roller 30 and the end-roller 32 of the traveling platform are rotated, is so proportioned that the roller 28 moves at a velocity slightly exceeding that of the platform and the guide-roller 30 rotates at greater speed than the friction-roller 28, for the purpose of 80 holding the sheets moving onto the coating roller, in a tense condition and thereby preventing their buckling, bending or folding.

The dipping roller is rotated at a velocity slightly exceeding that of the coating roller 85 for the purpose of obtaining a slight scraping effect which prevents the accumulation of dirt on their engaging surfaces.

The sheets to be coated are placed in a stack on the moving platform against the 90 gate and they are held against sidewise displacement by a plate 46 which is adjustably supported on the bars 35 to which the gate is secured.

The movement of the rubber belts 31 of 95 which the platform is composed, causes the lowermost sheet of the stack to pass through the space beneath the gate and into engagement with the friction rollers which continue its movement toward the coating 100 roller.

The movement of the sheets by the action of the traveling belts is obviously due to frictional contact therewith and it is more than probable that after one of the sheets 105 has passed partially through the space beneath the gate, the forward portions of the belts are frictionally engaged by the next following sheet or sheets.

If the surface of the sheets is embossed or 110 otherwise roughened, the frictional contact of the sheets above the lowermost one, with the belts, may cause a second sheet to be crowded through the space beneath the gate before the lower sheet has cleared the same, 115 with the result that the sheets are fed onto the coating roller in overlapping relation.

To prevent an occurrence of this character, an adjustable tilting element is provided which operates to raise the stack of 120 sheets partially off the surface of the traveling platform. The extent of the contact of the sheets with the belts may, by adjustment of this tilting element, be varied according to the roughness of their surface 125 and the frictional adherence between the belt and the sheets can thus be regulated so that the sheets will be separately and successively moved through the space beneath the gate.

The tilting element consists of a series of parallel slats 47 movably mounted on a rod 48 between the upper ends of two arms 49 which are pivotally connected with the side plates and are held in their adjusted position by clamping nuts 50.

The free ends of the slats rest upon one of the rollers 32 within the spaces between the endless belts and it will be seen that by changing the angle of inclination of the arms 49 the distance between the ends of the slats and that of the moving platform may be varied to lift the paper off the belts to any desired extent.

15 The sheets which were moved onto the table 29 by the action of the friction rollers, pass underneath the guide-roller 30 which causes them to engage the liquid-carrying surface of the coating roller which is continuously kept in a moist condition by contact with the dipping roller.

20 The adhesive liquid carried by the coating roller is thus transferred to a surface of the sheets which subsequently are compelled to separate from the surface of the roller by engagement with the curved edges of the lifting fingers 21.

25 The lifted sheets are by these means transferred onto the before-mentioned endless belt conveyer which carries them to a remote point of discharge.

30 The belt conveyer which is made of canvas or other suitable material, preferably absorbent, is mounted upon a series of rollers one of which, 51, extends above and in close proximity to the curved edges of the lifters 21 while the others, 52, 53, 54, 55 and 56 are mounted in an elevated position upon two parallel rails 57 of a superframe of the supporting structure.

35 The lower portion of the belt passes over a roller 58 which dips into a water-pan 59 supported between two uprights 60 of the frame, for the purpose of moistening the outer surface of the belt.

40 A roller 61 which is mounted upon a pair of levers 62 fulcrumed on the uprights 60, serves to lift the belt off the moistening roller to discontinue the supply of moisture thereto.

45 An idle roller 55 in conjunction with a dipping roller 56, supports the lower portion of the belt at the opposite end of the frame and a sag of the belt between these rollers and the roller on the lever 62 is engaged by a tension roller 63 at the lower ends of two arms 64 slanting downwardly from the rails 57, for the purpose of maintaining the upper stretch of the belt in a constantly taut condition.

50 The belt is wetted by the roller 58 for the purpose of preventing curling of the liquid-coated sheets, by the application of moisture to their lower uncoated surfaces, and to further promote the delivery of the sheets

55 in a perfectly flat condition and prevent their displacement on the belt, a series of endless chains 65 are placed on pulleys 67 and rollers 68 and 69 above the upper stretch of the belt, to engage the sheets of paper 70 supported thereon.

60 The chains which extend parallel in longitudinal relation to the upper stretch of the belt, move in the same direction and by engaging the coated upper surface of the sheets of paper as they move onto the belt from the edges of the lifters, prevent their displacement while keeping them at the same time in a flat condition.

65 In order to remove any adhesive that may be transferred to the chains from the coated sheets with which they come in contact, a roller 70 of felt or other absorbent material, saturated with water, is mounted between two standards 71 on the frame to engage the chains as they pass across the roller 68.

70 The forward roller 69 upon which the chains are supported is placed at a distance rearward of the adjacent end roller 54 of the belt 20, to compel the chains to disengage the sheets and permit of their removal from the belt before they reach the forward end thereof.

75 The rollers 51 and 67 upon which the belt and the chains are supported at their rear-most ends are mounted on two arms 72 which are pivoted as at 73 at the upper ends of the side plates 6 and which are held in their normal position by means of clamping nuts 74.

80 This arrangement affords a ready means for obtaining access to the dipping and coating rollers and the lifters supported upon the latter, by displacing the superposed parts of the belt and chains which is readily accomplished by turning the arms 72 about their pivots as shown in broken lines in Fig. 6 of the drawings.

85 The different elements of the coating machine thus described are connected to operate in conjunction by a driving and power-transmission mechanism which in the construction shown in the drawings receives its motion from a conveniently disposed motor 75.

90 A driving shaft 76 on the machine is connected with a countershaft 77 on the lower portion of the supporting structure by a belt 78 and the countershaft receives its movement from the motor through the medium of a belt 79.

95 The rotative continuity between the driving shaft and the pulley with which the belt engages, is established through the intermediary of a clutch 80 the adjustable part of which is by means of a system of rods 81 and 82 and co-operating levers 83, 84 and 85 connected with a pedal 86 at the forward end of the machine.

100 When the machine is used in coating

covers for boxes or other articles of manufacture, the machine by which the covers are applied to the frames of the boxes is placed adjacent the forward end of the 5 coating machine, and by placing the controlling levers of the latter at the same end, both machines can be operated by one person who is within easy reach of the forward end of the belt 20 to remove the coated 10 sheets and who controls the operation of the coating machine by pressure of the foot upon the pedal 86.

The driving shaft 76 carries at one of its ends a gear-wheel 87 which meshes with a 15 gear-wheel 88 on one of the trunnions of the dipping roller and it also carries a sprocket-wheel 89 which by a chain 90 is operatively connected with a corresponding wheel 91 of smaller diameter on a stud-shaft 92 secured to the adjacent side plate 6. A gear-wheel 93 on the stud-shaft meshes with the gear-wheel 45 on the lower friction roller and also with the pinion 33 which as stated before, connects with the 25 rear end-roller of the series upon which the belts 31 of the traveling platform are supported.

The pinion 33 is loosely mounted on a gudgeon of the roller and its rotative continuity therewith is secured or broken by moving it along the gudgeon through the medium of a crank-shaft 94 and a rod 95 operatively connected with a hand-lever 96 at the forward end of the machine.

35 The movement of the forward end roller of the series is transmitted to that at the opposite end of the same by means of the before-mentioned chain 34 which for safety is inclosed by a casing 97.

40 The dipping roller transmits its rotary movement to the coating roller by the engagement of its gear-wheel 88 with a similar gear-wheel 98 mounted at an end thereof, and the coating roller carries further- 45 more a sprocket-wheel 99 for its driving connection with the endless belt.

This connection is established through the medium of the before-mentioned friction roller 56 which engages the lower portion of 50 the belt immediately beneath the roller 52 upon which its upper stretch is supported, and which has a sprocket wheel 100 connected with the other sprocket-wheel by a chain 101.

55 The gear-wheel 98 on the coating-roller transmits its rotary motion to a gear-wheel 104 on the shaft upon which the pulleys 67 of the chains are mounted, through the medium of an intermediate gearwheel 105 on 60 the lower roller 51 of the belt-conveyer 20, and it furthermore meshes with the pinion 103 of the guide-roller 30.

Inasmuch as the operation of the machine has been explained at intervals in the course 65 of the foregoing description it will only be

necessary to outline it very briefly at this point.

The sheets being placed in a stack upon the traveling platform in engagement with the plate 46 and the gate 26, are moved singly and successively through the space 102 beneath the gate by the inovement of the rubber belts 31.

The gate has been previously raised or lowered in accordance with the thickness of 75 the material of which the sheets are composed, and the tilting element has been adjusted to prevent a second or third sheet from being crowded through the space beneath the gate by frictional contact with the 80 belts.

The sheets passing underneath the gate enter between the friction rollers 27 and 28 which carry them onto the table 29 beneath the guide roller 30 which compels them to 85 move into engagement with the liquid-carrying surface of the coating roller.

This roller is constantly kept in a moist condition by engagement with the dipping roller which moves through the liquid contained in the pan 3 and the bar 17 removes dirt and other solid foreign matter from the surface of the dipping roller before it engages the coating roller and thereby prevents all impurities contained in the liquid 95 from being transferred to the sheets.

After the sheets have been coated by contact with the moistened surface of the roller 9, they are lifted onto the endless belt 20 by engagement with the lifters 21, it being 100 observed that by reason of the position of the ends thereof within the grooves of the coating roller they provide a smooth and even path along which the sheets may move unobstructed onto the upper surface of the 105 belt.

The chains 65 engaging the coated upper surfaces of the sheets, hold them in place upon the belt, and the moisture imparted to the belt by the rollers 58 co-operates with the 110 chains to keep the sheets continuously in a perfectly flat condition.

The thickness of the coating to be applied to the sheets is regulated by adjustment of the dipping roller through the medium of 115 the levers 14, which varies the distance between its circumferential surface and that of the coating roller.

The operator may discontinue the operation of the entire machine or that of the 120 feeding mechanism only, by adjustment of the pedal 86 and the lever 96 at the forward end of the machine and when it is desired to clean the parts of the machine which come in contact with the coating liquid after the work is finished, the pan 3 is removed by sliding it along the slanting surface of the support 4 and replaced by a pan filled with clean water.

The arms 72 are moyed about their pivots 125 130

to remove the portions of the belt and the chains above the operating mechanism and by setting the machine in motion every part may thus be cleaned without disturbing its arrangement with relation to the other parts.

Having thus described my improved coating machine in the best form at present known to me I desire it understood that variations in the construction and arrangement 10 of its parts may be resorted to within the spirit of my invention as set forth in the following claims.

What I claim and desire to secure by Letters-Patent is:

- 15 1. In a coating machine, a coating-roller, means for feeding sheets thereto, a pan, a dipping roller coöperating with the coating roller and moving through the pan, and supporting-means adapted to hold the pan 20 in either an operative or an inoperative position and including a slanting surface for the sliding support of the pan during its movement from one position to another.
- 25 2. In a coating machine, a coating roller, a dipping roller tangent to the coating roller to transfer a liquid carried upon its circumferential surface thereto, and a rotatable support for the dipping roller, the axis of the dipping roller being eccentrically 30 mounted in said rotatable support.
- 35 3. In a coating-machine, a coating-roller, a dipping roller adjoining the coating roller to transfer a liquid carried upon its circumferential surface, thereto, bearings, bushings in the bearings, having eccentric openings in which the dipping roller is rotatably supported, and means to rotate the bushings in the bearings whereby to regulate the distance between the rollers.
- 40 4. In a coating machine, a coating roller having relatively narrow circumferential grooves, means for guiding sheets to the roller, lifters for causing the sheets to separate from the roller, each lifter having a narrow portion of substantially the width of, and extending into, an associated groove, another portion for guiding and directing sheets upwardly and reversely, and wipers 45 each having a portion extending into and substantially filling its associated groove at the zone of entry thereinto for the removal of entering matter.
- 55 5. In a coating-machine, a coating-roller having circumferential grooves, means for feeding sheets to the roller, lifters causing the sheets to separate from the roller, and extending freely in the grooves thereof, and wipers extending in the grooves for the removal of entering matter.
- 60 6. In a coating machine, a dipping roller, a coating roller in contact therewith and having circumferential grooves on its surface, and wipers extending into said grooves in the zone of tangency between the rollers.
- 65 7. In a coating machine, a dipping roller,

a coating roller contacting therewith and having circumferential grooves, means for feeding sheets to the coating roller, lifters extending into the grooves of the coating roller for stripping the sheets therefrom 70 and wipers extending into and substantially filling the grooves in the zone of tangency between said rollers and acting in advance of the lifters.

8. In a coating-machine, a coating-element, means for feeding sheets thereto, an endless belt to carry the sheets from the coating-element to a point remote herefrom, a water-bath, a roller moving through the bath and in engagement with the outer 75 surface of the belt, and means for separating the belt from the roller.

9. In a coating-machine, a coating element, means for feeding sheets thereto, an endless belt to carry the sheets from the 80 coating element to a point remote therefrom, and flexible traveling means having a loose run portion resting by gravity upon the carrying portion of the belt to hold the sheets in place thereon and having a relatively limited portion in contact with the sheets.

10. In a coating-machine, a coating element, means for feeding sheets thereto, an endless belt to carry the sheets from the 85 coating element to a point remote therefrom, and endless flexible means having a loose run portion resting by gravity upon the carrying portion of the belt and traveling with the same to hold the sheets in 90 place, said loose run portion having a relatively limited portion in direct contact with the sheets.

11. In a coating-machine, a coating-element, means for feeding sheets thereto, an 95 endless belt to carry the sheets from the coating-element to a point remote therefrom, and endless chains engaging the carrying portion of the belt and traveling with the same.

12. In a coating-machine, a coating-element, means for feeding sheets thereto, an 100 endless belt to carry the sheets from the coating-element to a point remote therefrom, endless chains engaging the carrying portion of the belt and traveling with the same, and means for cleaning the chains 105 from adherent matter.

13. In a coating-machine, a coating-element, means for feeding sheets thereto, an 110 endless belt to carry the sheets from the coating-element to a point remote therefrom, endless chains engaging the carrying portion of the belt and traveling with the same, and a roller of absorbent material 115 engaging the chains to clean them of adherent matter.

14. In a coating-machine, a coating-element, means for feeding sheets thereto, an 120 endless belt to carry sheets from the ele- 130

ment to a point remote therefrom, and a support for the belt, adapted for adjustment to displace the portion of the same adjoining the coating-element.

- 5 15. In a coating-machine, a coating-element, means for feeding sheets thereto, an endless-belt to carry sheets from the element to a point remote therefrom, endless chains resting upon the carrying portion of the belt, and a support for the belt and the chains adapted for adjustment to displace the portions of the same adjoining the coating element.
- 10 16. In a coating-machine, a coating-element, means for feeding sheets thereto, an endless belt to carry sheets from the element to a point remote therefrom, endless chains resting upon the carrying portion of the belt, rollers for the support of the belt and 20 the chains adjacent the coating-element, pivoted arms on which the rollers are supported, and means for locking the arms in their normal position.

17. In a coating-machine, a coating-25 roller, and feeding-mechanism including a traveling platform, feed-rollers for moving sheets from the platform toward the coating roller, a guide roller for moving the sheets onto the same, and transmission mechanism 30 which rotates the guide-roller at a greater speed than the feed-rollers and rotates the latter at a velocity exceeding that of the traveling platform.

18. In a coating machine, a coating-35 roller, and feeding-mechanism including feed rollers for moving sheets toward the coating-roller, and a guide roller for moving the sheets onto the same and transmission-mechanism which rotates the guide-40 roller at a velocity exceeding that of the feed-rollers.

19. In a coating machine, a coating-45 roller, and feeding-mechanism including a traveling platform, feed-rollers for moving sheets from the platform onto the coating-roller, and transmission-mechanism which rotates the feed-rollers at a velocity exceeding that of the platform.

20. In a coating machine, a coating-50 roller having circumferential grooves,

lifters each having a portion located in a groove, another portion adapted to turn and direct the sheets in a reverse direction, a conveyer belt having an upwardly inclined portion extending from a point 55 above the coating roller and adjacent the lifters, another substantially horizontal portion, and an endless chain trained to have a portion thereof contact and travel with the said inclined and horizontal portions of 60 the belt.

21. In a coating machine, a coating element, a belt for conveying the sheets from the coating element to a delivery station, and endless retaining means resting by 65 gravity upon and traveling with said belt to a point short of the delivery station for the purpose of lifting the conveying belt free of the retaining means at the delivery station for the convenience in removing the 70 sheets.

22. In a coating-machine, a coating element, a belt for conveying the sheets away from the coating element and having a substantially horizontal portion, and an end-75 less retaining band having a loose run lower flight with a relatively limited portion resting on said horizontal portion of the belt and an upper flight carried by a plurality of rollers having surfaces equally spaced from 80 the adjacent portion of the belt by a distance substantially greater than the thickness of the retaining band so that the lower flight rests on the horizontal portion of the belt by gravity only and free from pressure 85 by the rollers.

23. In a coating machine, a dipping roller and a coating roller contacting therewith and having its axis laterally spaced from the vertical plane through the axis of the 90 dipping roller to form a glue pocket between said rollers, said coating roller having circumferential grooves, wipers extending into said grooves in the zone of tangency of the rollers and substantially filling the 95 grooves; and means for removing sheets from the coating roller.

In testimony whereof I have affixed my signature.

ALFRED J. MORRISON.
